CLAIM

The ornamental design for a diagnostic apparatus as shown and described.

DESCRIPTION

FIG. 1 is a perspective view of the diagnostic apparatus of our new design;

FIG. 2 is a front view thereof;

FIG. 3 is a right-side view thereof, the left-side view being a mirror image thereof;

FIG. 4 is a rear view thereof;

FIG. 5 is a top view thereof; and,

FIG. 6 is a bottom view thereof.

The broken lines depict structure that form no part of the design to be patented.

1 Claim, 6 Drawing Sheets
